UNITED STATES PATENT OFFICE.

FRED FULGORA, OF McCANDLESS TOWNSHIP, ALLEGHENY COUNTY, PENNSYLVANIA.

MECHANICAL GAME DEVICE.

Application filed August 6, 1928. Serial No. 297,690.

The object which I have in view is the provision of a mechanical device which may be operated in accordance with various games, such for instance games in which playing 5 cards, dice and the like are employed to indicate playing values.

In general my improved mechanical game device is characterized by the employment of rotary disks, having depicted on their faces 10 the representation of playing cards, dice-faces or other playing values, and moving in relation to apertures in a covering lid, the disks being spun by means of a manually advanced and spring-return rotary driving 15 wheel whose perimetral surface is arranged for frictional contact with annular surfaces concentric and moving in unison with the disks, the frictional surface of the driving wheel however being interrupted in such a 20 manner that after the disks have been given a spinning movement by the spring-return of the driving wheel, the disks continue their spinning after the driving wheel has come to rest.

Another characteristic of my present invention is the provision of means whereby when a disk comes to rest, one of the playing cards, dice-faces or other indicia carried by 30 the disk is fully exposed at the corresponding aperture.

Another characteristic of my invention is the provision of means whereby one or more of the disks may be retracted in relation to the driving wheel so that the rotation of the 35 driving wheel will not result in spinning the disk or disks.

Other novel features of construction, and also of arrangement of parts, will appear from the following description.

In the accompanying drawings, wherein I have illustrated a practical embodiment of 40 the principles of my invention, Fig. 1 is a plan view of my invention developed to display hands of playing cards, a portion of the lid being cut away to expose one of the disks.

Fig. 2 is a vertical section taken along the irregular line 2-2 in Fig. 1.

Fig. 3 is an enlarged detail partially in 50 section and showing one of the disk carriages,

the friction wheel of the corresponding disk and a portion of the driving wheel.

Fig. 4 is a view partially in section and partially in side elevation of one of the disks and its carriage. 55

Fig. 5 is a plan view showing my invention developed as a dice-throwing device.

Fig. 6 is a longitudinal, vertical section of the same.

Referring first to Figs. 1 to 4, inclusive, 60 1 represents the base which may be of wood or metal and is preferably circular in form.

Mounted on the base is a low circular wall 2 which may be of sheet metal.

A post 3 rises from the base at the axial 65 center of the wall 2.

The upper end of the post 3 is threaded, and 4 represents a lid, which may be of sheet metal and which fits down on the circular wall 2 and has a central opening through 70 which the post 3 protrudes. The post may be provided with a circumferential shoulder 5 to support the lid. A nut 6 may be screwed onto the upper end of the post to hold the lid in place. 75

7 represents a driving wheel of wood or other material which is mounted co-axially with the post 3 within the wall 2 and is supported above the base 1 as by a collar 8 on 80 said post.

The wheel 7 is hollowed downwardly to form a spring-chamber 9 concentric with the axis of the wheel, and within said chamber is mounted the spiral driving spring 10 whose one end is fixed to the post 3 and its 85 other end to the wheel 7, so that by rotating the wheel in the proper direction, clockwise in Fig. 1, the spring 10 is wound up and the wheel when released, will be spun in a counterclockwise direction by the expanding 90 spring.

11 represents a sheet metal cover for the spring chamber 9.

The perimetral edge of the wheel 7 is provided with a frictional contact surface 12 95 which may be of rubber or similar material.

The perimetral surface is not continuous but is provided with inwardly sunken interruptions or recesses, such as shown at 13 in Fig. 3. Such interruptions are equal in num- 100

ber to the playing disks hereinafter described.

14 represents handles extending radially from the wheel 7 and protruding through circumferentially disposed slots in the circular wall 2, whereby the wheel may be manually rotated to wind up the spring 10.

The base 1 is provided with a plurality of sideways 15 disposed radially relative to the post 3, and in said sideways are mounted the flat bases of the disk-carriages 16, the outer end of said bases protruding through apertures in the wall 2, and being provided with handle-knobs 17 so that the carriages may be individually retracted outwardly or pushed inwardly as shown.

When at their inner positions, as shown at the right in Fig. 2, the carriages are held fixed by the spring latches 18 mounted on the base and overhanging the sideways to engage notches 19 in the inner ends of the carriages.

Each of the carriages 16 is provided with an angular bracket 20.

21 represents the playing-disks which are each provided with a depending axial spindle 22 fixed to the disk.

The spindle 22 extends down through and is journaled in a hole in the horizontal leg of the bracket 20 and has its lower end journaled in a step bearing in the base of the carriage.

23 represents an annular friction wheel fixed on the spindle 22 below the horizontal leg of the bracket 20.

When a carriage is in its inner position, the corresponding friction wheel 23 is in the path of the friction surface 12 of the driving wheel 7, so that the disk is spun by the wheel 7 while said wheel is rotating, but when the wheel 7 comes to rest, its interruptions 13 are positioned opposite the friction wheels 23, thus permitting the disks to continue to spin after the driving wheel has come to rest.

The perimeters of the friction wheels 23 may be roughened or serrated to improve their frictional engagement with the driving wheel 7.

50 The upper faces of the disks 21 have depicted thereon in annularly arranged series various indicia of playing values.

Thus I have shown the representation of playing cards depicted on the disks, and the lid 4 is provided with a number of apertures 24 equal in number of the disks, at which, when the disks come to rest, a playing card is exposed by each disk.

To insure the proper centering of the playing cards relative to the apertures, the friction wheels 23 are provided on their upper surfaces with an annular series of sockets 25 which are engaged by the depending spring-ball detent 26 carried by the bracket 20, the sockets being so arranged relative to the play-

ing cards on the disk that as the disk slows down after being spun and the detent halts the disk by engaging one of the sockets, the disk is halted with one of the playing cards fully exposed at the corresponding aperture. 70

The disks are supplied in number equal to the number of cards which form a hand in the game being played.

I have shown five disks so that the device may be employed to indicate hands in a game 75 wherein a five card hand is used.

If the device is to be employed to indicate whist hands, thirteen disks are supplied.

The disks have displayed thereon the fifty-two cards of the pack, grouped as nearly in 80 equal number as possible. Thus in a thirteen card hand game each disk would display four cards, while in a five card hand game three disks would display ten cards and two disks would display eleven cards. 85

When it is desired to retain the values displayed on one or more disks and to obtain new values on the remaining disk or disks, the carriages of the disks which are to retain their values are pulled outwardly, as 90 illustrated at the left in Fig. 2, so that their friction wheels 23 are drawn away from possible contact with the driving wheel 7, so that upon the next operation of the device, the remaining disk or disks only will be spun. 95

The retraction of the carriage is not sufficient in extent to prevent the playing card being read at the aperture.

In Figs. 5 and 6 I have shown the device developed as a dice throwing device which 100 may be used in connection with various games, such for instance as games wherein playing objects are advanced on a game board in accordance with the values thrown by the dice.

In this form of my device the base 1^a, the surrounding wall 2^a and the lid 4^a may be rectangular as but two playing disks 21 are used, one for each dice.

Each of the disks have displayed on their 110 upper faces the six faces of the dice and one of said dice faces is exposed at the corresponding aperture 24 after each spinning of the disks by means of the drive wheel 7.

In this case the sliding carriages are not 115 required and the upper ends of the spindles 22 are journaled in holes in the lid 4^a.

The sockets 25 are on the lower faces of the frictional wheels 23 and the detents 26^a extend upwardly from the base. 120

There is a decided advantage in providing the driving wheel with the interruptions in its frictional contact surface, as the disks are thus permitted to spin freely and individually when the driving wheel comes to rest. 125

What I desire to claim is:—

1. In a game apparatus of the character described, the combination of a casing having an apertured lid, a driving wheel rotatably mounted in said casing and arranged 130

- to be manually rotated in one direction and to be spring-returned in the other direction, a disk rotatably mounted within said casing and having its surface provided with 5 indicia of playing values which are arranged so as to be singly exposed at the aperture in the lid by the movement of the disk, an interrupted contact surface on the perimeter of said driving wheel, and an annular contact surface moving with and concentric with the axis of said disk and so disposed as to be engaged by the contact surface of said driving wheel when the latter is rotating whereby to spin the disk.
- 10 2. In a game apparatus of the character described, the combination of a casing having an apertured lid, a driving wheel rotatably mounted in said casing and arranged to be manually rotated in one direction and to be spring-returned in the other direction, a disk rotatably mounted within said casing and having its surface provided with 15 indicia of playing values which are arranged so as to be singly exposed at the aperture in the lid by the movement of the disk, an interrupted contact surface on the perimeter of said driving wheel and an annular contact surface moving with and concentric with the axis of said disk and so disposed as to be engaged by the contact surface of said driving wheel when the latter is rotating whereby to spin the disk.
- 20 3. In a game apparatus of the character described, the combination of a casing having an apertured lid, a driving wheel mounted in said casing and arranged to be manually rotated in one direction and to be spring-returned in the other direction, a plurality of disks having their faces provided with 25 concentrically arranged series of indicia of playing values which are singly exposed at the apertures of said lid by the movement of the disk, frictional contact means whereby the disks may be spun by the rotation of said 30 driving wheel, and means whereby the frictional contact between individual disks and the driving wheel may be independently interrupted.
- 35 4. In a game apparatus of the character described, the combination of a casing having an apertured lid, a driving wheel mounted in said casing and arranged to be manually rotated in one direction and to be spring-returned in the other direction, a plurality of 40 disks having their faces provided with concentrically arranged series of indicia of playing values which are singly exposed at the apertures of said lid by the movement of the disk, frictional contact means between each of the disks and the driving wheel when the corresponding carriage is in its inner position whereby to spin the disk by the rotation of the driving wheel, said engagement being interrupted by the drawing out of the corresponding carriage.
- 45 5. In a game apparatus of the character described, the combination of a casing having an apertured lid, a driving wheel mounted in said casing and arranged to be manually rotated in one direction and to be spring-returned in the other direction, a disk rotatably mounted on each of said carriages and having 50 its face provided with a concentrically arranged series of indicia of playing values which are singly exposed at the apertures of said lid by the movement of the disk, frictional contact means between each of the disks and the driving wheel when the corresponding carriage is in its inner position whereby to spin the disk by the rotation of the driving wheel, said engagement being interrupted by the drawing out of the corresponding carriage.
- 55 6. In a game apparatus of the character described, the combination of a casing, an apertured lid for said casing, a driving wheel mounted in said casing and arranged to be manually rotated in one direction and to be 55 spring-returned in the other direction, a disk rotatably mounted in said casing and having its face provided with a concentric series of 60 indicia of playing values which are singly exposed at the aperture in said lid by the

movement of the disk, a contact wheel mounted concentrically with the axis of said disk and moving in unison therewith, said contact wheel having frictional engagement with said driving wheel whereby to spin said disk, a spring-ball detent having a fixed mounting in said casing and sockets on said contact wheel so disposed relative to said indicia so that the disk when halted is properly positioned relative to the aperture. 10
